ROUNDING MACHINE

Charles G. Brostrom, Salem, and Walter E. Naugler, Beverly, Mass., assignors to United Shoe Machinery Corporation, Flemington, N. J., a corporation of New Jersey

Application April 3, 1942, Serial No 437,482

17 Claims. (Cl. 12—85)

This invention relates to machines by which work-pieces are rounded or formed as to their contour, it having to do particularly with machines for operating upon shoe-soles, an example of which is furnished by that disclosed in Letters Patent of the United States No. 2,319,296, Brostrom, May 18, 1943.

In the manufacture of shoes, it may be desired to produce upon a part, indicating means which will serve during later steps to guide the operator or to control the operation of a machine. It is an object of the present invention to effect a change of form of an element, as a shoe-sole, for this or an analogous purpose, by means which is simple, effective and readily governed by the operator.

The above end is gained by combining, in a rounding machine, a rounding knife or cutter movable into and out of engagement with the work, as by its reciprocation, means for feeding the work to receive the action of the knife, and means for moving the work and knife relatively to each other for a predetermined number of its reciprocations. There is thus caused a departure from the rounded contour normally produced; this giving, for example, a projection from a sole-edge which may serve the controlling function above referred to. The knife preferably has a cutting edge which will remove successive pieces from the work, and, when the relative movement between the work and knife occurs, there will be formed a projection from the rounded edge, the extent of which depends upon the number of reciprocations during which the knife was out of its normal position. As herein disclosed, the change in the rounded contour results from movement of the knife, actuated under the power of the machine and controlled by the operator. The knife preferably reciprocates upon a movable bearing, which has movable upon it a contact member normally lying out of the path of movable actuating means, which may include a continuously rotatable cam. Under the influence of means controlled by the operator, the contact member may be shifted into the path of the actuating means to produce the desired movement of the bearing. Upon such movement, the operator-controlled means releases the contact member, leaving the time of engagement between it and the actuating means dependent upon the form of the cam and therefore predetermined.

One of the several possible embodiments of the invention is illustrated in the accompanying drawings, in which

Fig. 1 is a partial front elevation of the improved rounding machine;

Fig. 2, a broken side elevation thereof, with the knife in its normal relation;

Fig. 3, a detail in broken side elevation showing the knife elevated by its actuating cam to produce the projection from the rounded edge;

Fig. 4, a front elevation of said controlling mechanism as positioned in Fig. 3;

Fig. 5, a bottom plan view of a portion of a shoe-sole, this illustrating the normal contour of the rounded edge with the projection produced by the machine of this invention; and

Fig. 6 is a separated perspective view of the elements by which the knife is raised above the normal line of action.

A rounding machine to which the invention may be applied, requires description only as to its general characteristics. Upon a head 10 supported by a column 12 is carried a bearing 14 for a reciprocating spindle 16. At the forward extremity of the spindle is mounted for vertical adjustment a chopping-knife 18, cutting against an anvil 20 fixed in a bracket 22 depending from the front of the head. The spindle 16 is joined by a link 24 to a crank-pin 26, revolved by a shaft 28 journaled transversely of the head and rotated through gearing 30 from a countershaft 32, having a bearing in the head and driven by belt-gearing 34 from an unillustrated source.

The work, which may be a sole S attached to a shoe-upper U (Fig. 3), is advanced to receive the action of the rounding knife by rotatable feed-rolls 36 and 38. The roll 36 is fixed upon the lower end of a downwardly and outwardly inclined shaft 40, journaled in a bearing 42 adjustable as to angle upon a block 44 and also adjustable vertically by the positioning of said block upon the head. This roll 36 has an angular toothed periphery, arranged to enter the crease of a shoe to gage it, and advance it as indicated by the arrow in Fig. 1. It is driven from a motor 46 through belt-gearing 48, reducing gearing enclosed in a casing 50, and through intermediate connections to sprocket-gearing 54 and spiral-gearing 56. The roll 38 is adapted to engage the tread-surface of the sole; it being rotatable about a vertical axis upon a slide 58 movable horizontally on the head 10 and urged normally toward the roll 36 by a tension-spring 60 (Fig. 2). The slide and roll may be retracted for the introduction of the work by a bell-crank-lever 62, connected to an unillustrated treadle. Rotation is imparted to the roll 38 from the sprocket-gear-

ing 54, through sprocket-gearing 64, spiral-gearing 66 and spur-gearing 68.

Considering now the mechanism more directly involved in the present invention, the bearing 14 for the rounding-knife-spindle is pivoted at 89 upon the head, being held normally down by a tension-spring 82, to locate the knife 18 for such action against the anvil 20 as to produce the normal rounded edge upon the sole positioned between the rolls 36 and 38. The cutting edge 84 of the knife is shown as arcuate, with its closed side down, it being adapted to remove successively from the sole-edge separate pieces, which, by overlapping, may be caused to form an edge departing but little from a continuous curve. Pivoted at 86 upon the bearing 14 (Figs. 2, 3 and 4) is a contact member 88, the downwardly extended lower portion of which is pressed against a vertical wall 90 upon the head 10 by an expansion-spring 92, interposed between the upper portion of the contact member and the bearing. Pivoted upon a forward projection 94 from the head 10 is an arm 96, having rotatable upon its inner extremity a roll 98 drawn by a tension-spring 100 into contact with the periphery of a cam 102. The cam and arm furnish actuating means for the bearing 14 to move the knife laterally upward, such means being in continuous operation during the use of the machine but normally ineffective. For this operation, the shaft 104 of the cam, which is journaled transversely of the head, may, by a spur-gear 106, intermediate gearing 108 (Fig. 1) and a pinion 110, be constantly driven from the shaft 28 of the rounding-knife.

In the normal action of the knife 18 upon the sole-edge, the end 112 of the arm 96 oscillates idly in an angular space 114 in the contact member 88 (Fig. 2), the spring 92 holding a shoulder 116 upon the member clear of the arm. To enable the operator to produce upon the sole-edge the projection or other departure from the normal rounded contour, and at the desired point, a controlling rod 118 is joined to a treadle or other element arranged for actuation by the operator. As is customary, this operator-controlled rod is held normally elevated by a spring which is not shown. This urges a collar 120 (Figs. 1 and 2) fast upon the rod against the underside of the arm 122 of a multiarm-lever L, fulcrumed upon a bracket 124 projecting horizontally from the head 10. The movement of the rod and lever in this direction is variably limited by the contact of a screw 126, threaded through the upper portion of the divided end of an arm 128 of the lever, with a projection 130 from the bracket 124. Upon a third and upwardly extending arm 132 of the lever L is pivoted a substantially horizontal shifting dog 134 for the contact member 88, it having an angular end 136 for engagement with a projection 138 from the side of said member. The dog is forced up, so either its body-portion (Fig. 2) or its end 136 (Fig. 3) may bear against the projection 138, by an expansion-spring 140. This spring is seated in a depression in a lug 142 upon one side of the lever-arm 132 and supports the dog. A screw 144, threaded through a depending portion of the dog and contacting with the side of the lug, limits the upward movement of the end 136. The rod 118 passes upwardly from the collar 120 through the end of the lever-arm 122, above which it is surrounded by a compression-spring 146, resting at its lower end upon the lever-arm and abutting at its upper extremity against a collar 148 fast upon the rod.

As to the operation of the machine, the ele-

ments are initially as appears in Fig. 2 of the drawings. The knife 18 is in constant reciprocation into and out of cutting relation to the anvil 20, while the feed-rolls 36 and 38 are similarly rotated. Drawing back the roll 38 through the slide 58 and lever 62, the operator applies the crease of a shoe to the angular periphery of the roll 36, and frees the roll 38 for engagement with the tread-surface of the sole. The work is thereby advanced, guided by the roll 36 while the knife rounds the sole-periphery to a contour normally corresponding to that of the crease. Although the arcuate edge of the knife removes from the sole-edge a series of discrete chips, the rate of advance of the work and of reciprocation of the knife are so related that the rounded edge presents an almost smooth surface. When there is reached a point in the sole-edge at which the operator wishes to produce an indicating or controlling projection, he draws down the rod 118. The movement of the actuating cam 102 and arm 96 is continuous but, prior to actuation of the lever L, the end 112 of the arm will oscillate idly in the space 114 of the contact member 88 (Fig. 2). The movement of the rod, through the spring 146, depresses the lever-arm 122 yieldably to an adjustable extent permitted by the engagement of a screw 150, threaded through the lower branch of the lever-arm 128 with the bracket-projection 130 (Fig. 3). The resulting counter-clockwise movement of the lever-arm 132 carries the end 136 of the dog 134 against the projection 138 of the contact member, behind which projection it normally rests. This exerts a force tending to shift the lower end of the contact member to the left, and, when the cam 102 allows the actuating arm 96 to fall, the contact member is swung outwardly by the dog until the shoulder 116 is above the end 112 of the actuating arm. Now, for a period depending upon the form of the cam, the arm acting through the contact member will lift the bearing 14 against the tension of the spring 82, so the knife 18 is reciprocating above its normal line of action and removing smaller chips. There will thus be produced, as shown in Fig. 5, a projection P from the edge of the sole S. As long as the knife remains raised, the crest of the projection will have some peripheral extent. But for the number of knife-reciprocations which occurred during the formation of the projection illustrated, this being three, the return of the knife to normal will remove the greater part of said projection, leaving it pointed. This is desirable for certain purposes, but may be altered by a change in the cam. Upon the first elevation of the contact member 88 by the actuating arm, the projection 138 leaves the end 136 of the dog 134, so said dog is held by its spring 140 in the position appearing in Fig. 3, in which the end lies beneath the projection in a position determined by the screw 144. In spite of this release of the contact member by the dog, its shoulder 116 remains in engagement with the end 112 of the actuating arm, because of the friction between the two elements produced by the heavy spring 82. The operator, however, has lost control of the contact member, and therefore control of the knife is nullified, because of the ineffective relation of the dog. This continues for the chosen number of knife-strokes, as already indicated, until the cam 102 permits the spring 100 to lower the actuating arm, returning the knife to its normal position. When the spring 82 depresses the bearing 14 and knife 18, the operator may or may not have re-

leased the rod 118. In the first instance, the dog will have been so positioned by the lever L that the projection 138 will at once assume its normal relation, appearing in Fig. 2. In the second, the projection will strike and bear upon the top of the angular end 136 of the dog. But, as soon as the rod is freed by the operator, its collar 120 acts upon the lever L to shift the dog to the position of Fig. 2. Thus, regardless of the time of release of the rod 118 by the operator, the dog attains the correct relation to the projection of the contact member, ready for the succeeding operation.

Having described our invention, what we claim as new and desire to secure by Letters Patent of the United States is:

1. In a rounding machine, a rounding-cutter movable into and out of cutting engagement with the work for the production of a normal rounded contour, means for feeding the work to receive the action of the cutter, and means controlled by the operator and operating under the power of the machine for moving the work and cutter relatively to each other for a predetermined number of cutting movements to cause a departure from the rounded contour normally produced.

2. In a rounding machine, a reciprocating rounding-knife operative to produce a normal rounded contour, means for feeding the work to receive the action of the knife, and means controlled by the operator and operating under the power of the machine for moving the work and knife relatively to each other for a predetermined number of reciprocations of said knife to cause a departure from the rounded contour normally produced.

3. In a rounding machine, a reciprocating rounding-knife the cutting edge of which is formed to remove successive pieces from the work, an anvil against which the knife cuts, means for feeding the work across the anvil to receive the action of the knife, and means for moving the work and knife relatively to each other to cause the knife to remove smaller pieces from the work while the feed continues.

4. In a rounding machine, a reciprocating rounding-knife having an arcuate cutting edge, means for feeding the work to receive the action of the knife, and means controlled by the operator and operating under the power of the machine for moving the work and knife relatively to each other to change the action of the knife upon the work for a predetermined number of reciprocations.

5. In a rounding machine, a movable rounding cutter, means for feeding material bodily past the cutter for the production in the material of a normal rounded contour, and means operating under the power of the machine and controlled by the operator for moving the cutter to cause a departure from such normal rounded contour.

6. In a rounding machine, a movable rounding-cutter, means for feeding the work to receive the action of the cutter and including a gage contacting with said work to direct its advance past the cutter along a path to produce a normal rounded contour, and means operating under the power of the machine and controlled by the operator for moving the cutter to cause a departure from such normal rounded contour.

7. In a rounding machine, a movable rounding-cutter, means for feeding the work to receive the action of the cutter, and means actuated under the power of the machine as initiated by the operator for moving the cutter away from the

work and then returning it independently of operator-control to cause a departure of predetermined extent from the rounded contour.

8. In a rounding machine, a movable rounding-cutter, a movable bearing in which the cutter is movable to produce its cut, means for feeding the work to receive the action of the cutter, means for moving the bearing under the power of the machine, and means movable by the operator for controlling the movement of the bearing.

9. In a rounding machine, a movable rounding-cutter, a movable bearing in which the cutter is movable to produce its cut, means for feeding the work to receive the action of the cutter, means for moving the bearing under the power of the machine, means movable by the operator for controlling the movement of the bearing, and means acting as a result of the operation of the machine to nullify such control.

10. In a sole-rounding machine, a work-guide, a reciprocating rounding-knife co-operating therewith, a movable bearing in which said knife reciprocates, actuating means, a contact member movable upon the bearing and lying normally out of the path of the actuating means, and means controlled by the operator to shift the contact member into the path of the actuating means.

11. In a sole-rounding machine, a work-guide, a reciprocating rounding-knife co-operating therewith, a movable bearing in which said knife reciprocates, actuating means, a contact member movable upon the bearing and lying normally out of the path of the actuating means, and means controlled by the operator to shift the contact member into the path of the actuating means to produce movement of the bearing, said contact member being released by the operator-controlled means upon movement of the bearing.

12. In a sole-rounding machine, a work-guide, a reciprocating rounding-knife co-operating therewith, a movable bearing in which said knife reciprocates, actuating means, a contact member movable upon the bearing and lying normally out of the path of the actuating means, and means controlled by the operator to shift the contact member into the path of the actuating means to produce movement of the bearing, said contact member being released by the operator-controlled means upon movement of the bearing, operating engagement between the actuating means and contact member being frictionally maintained for a predetermined time.

13. In a sole-rounding machine, a reciprocating rounding knife, means for advancing material to present a margin to the rounding knife, a bearing in which the knife reciprocates, said bearing being movable to shift the knife transversely of the margin, a rotatable cam, and means actuated by the cam for moving the bearing during the reciprocation of the knife.

14. In a rounding machine, a reciprocating rounding-knife, a movable bearing therefor, a rotatable cam, an arm oscillated by the cam, a contact member movable upon the bearing into and out of the path of the arm, and a member movable by the operator to shift the contact member into the path of the arm.

15. In a rounding machine, a reciprocating rounding-knife, a movable bearing therefor, a continuously rotatable cam, an arm oscillated by the cam, a contact member movable upon the bearing into and out of the path of the arm, and a member movable by the operator to shift the contact member into the path of the arm for actuation thereby, the contact member being

released from the shifting member upon movement of the bearing.

16. In a rounding machine, a reciprocatory rounding-knife, a movable bearing therefor, a continuously rotatable cam, an arm oscillated by the cam, a contact member movable upon the bearing into and out of the path of the arm, a lever movable by the operator, and a dog pivoted upon the lever for engagement with the contact member.

17. In a rounding machine, a reciprocatory

rounding-knife, a movable bearing therefor, a continuously rotatable cam, an arm oscillated by the cam, a contact member movable upon the bearing into and out of the path of the arm, a lever, a dog yieldable upon the lever for engagement with the contact member, an operator-actuated rod, and a spring communicating movement of the rod to the lever.
